(57) **CLAIM**

The ornamental design for a grommet for an office partition panel, as shown and described.

DESCRIPTION

FIG. 1 is a front perspective view of a grommet for an office partition panel according to my new design;

FIG. 2 is a front/rear view thereof, wherein the front and rear views are identical;

FIG. 3 is a sectional view thereof, taken along line 3—3 of FIG. 2; and,

FIG. 4 is a sectional view thereof, taken along line 4—4 of FIG. 2.

The environmental structure shown in dashed lines forms no part of the claimed design.
